[57] CLAIM

The ornamental design for a combined food cutting board and measuring cup or the like, as shown.

DESCRIPTION

FIG. 1 is a top perspective view of a combined food cutting board and measuring cup or the like showing our new design;

FIG. 2 is a top plan view thereof;

FIG. 3 is an elevational view of the right side of FIG. 2;

FIG. 4 is an elevational view of the left side of FIG. 2;

FIG. 5 is an elevational view of the lower side of FIG. 2;

FIG. 6 is a bottom plan view thereof; and

FIG. 7 is an exploded perspective view of FIG. 1.
